(57) **CLAIM**

The ornamental design for single article packaging with flap, as shown and described.

DESCRIPTION

FIG. 1 is a perspective view of the single article packaging with flap showing an article positioned in the packaging in broken lines. The broken lines shown in any of the Figures are for the purpose of illustrating the environmental structure of the single article packaging with flap and are not part of the claimed design.

FIG. 2 is a front view of the single article packaging with flap of FIG. 1.

FIG. 3 is a back view of the single article packaging with flap of FIG. 1.

FIG. 4 is a left side view of the single article packaging with flap of FIG. 1.

FIG. 5 is a right side view of the single article packaging with flap of FIG. 1.

FIG. 6 is a top view of the single article packaging with flap of FIG. 1.

FIG. 7 is a bottom view of the single article packaging with flap of FIG. 1.

FIG. 8 is a perspective view of an alternative embodiment of the single article packaging with flap of FIG. 1.

FIG. 9 is a front view of the alternative embodiment of the single article packaging with flap of FIG. 8; and,

FIG. 10 is a top view of the alternative embodiment of the single article packaging with flap of FIG. 8.

1 Claim, 5 Drawing Sheets
